UNITED STATES PATENT OFFICE.

ANDREW B. LIPSEY, OF WEST HOBOKEN, NEW JERSEY, ASSIGNOR TO WILLIAM BELL, OF NEW YORK, N.Y.

GAS-BURNER.

SPECIFICATION forming part of Letters Patent No. 278,568, dated May 29, 1883.

Application filed March 24, 1883. (No model.)

To all whom it may concern:

Be it known that I, ANDREW B. LIPSEY, of West Hoboken, in the county of Hudson and State of New Jersey, have invented a certain new and useful Improvement in Gas-Burners, of which the following is a specification.

The object of this improvement is to produce a gas-burner in which the gas will be very thoroughly heated before arriving at the point of combustion.

The improvement consists in the combination, with an annular burner-tip or a series of burner-tips, of a gas-passage extending up within the same to a point considerably beyond the same and returning thereto, so as to be heated by the products of combustion passing through a chimney applied to the burner.

The improvement also consists in a novel manner of constructing and supporting a chimney for a burner.

In the accompanying drawings, Figure 1 is a central vertical section of a burner and appurtenances embodying my improvement. Fig. 2 is a plan of the burner, and Fig. 3 is a plan or top view of a certain part of the burner.

Similar letters of reference designate corresponding parts in all the figures.

The burner is provided with a socket, A, which is shown as internally screw-threaded, so that it may be attached to the nipple of a gas-fixture. This socket is shown as made integral with a body-piece, B, from which extend laterally a number of hollow arms or pipes, C, communicating with an annular burner-tip, D. The inner wall of this burner-tip is shown as made integral with the hollow arms or pipes C, and the outer wall and tip as made separately and screwed in place. In the top of the burner are small apertures, from which the gas may issue.

E designates a pipe extending from the body-piece B upward within the annular burner-tip to a point a long distance above the same. It communicates with the socket A, and, as here shown, is united at the upper end by a coupling-piece, E', with another pipe, E², of the same size, extending in line therewith. The pipe E² is closed at the upper end by a cap, a, or otherwise. Near its upper end a number of pipes, F, extend laterally from it, and from these pipes F pipes G extend downwardly

to the coupling-piece E'. These pipes F G are shown as six in number, and as much smaller than the pipe E². From the coupling-piece E' a large pipe, P, extends to a hub, b, formed upon the body-piece B. Between this pipe F and the pipe E² is left an annular space, which communicates with a cavity in the hub b, and thence with the hollow arms or pipes C. All these parts may be made of any suitable metal.

From the body-piece B extends a chimney-gallery, H, which may consist of a disk of sheet metal fastened to the under side of the body-piece by screws c or otherwise.

I J designate a chimney composed of two sections. The lower section, I, may be made of glass, and is supported upon the gallery H; but the upper section, J, will preferably be made of metal, and extends past the lower section, inside or outside of it. As here shown, the upper section, J, is provided with an inwardly-extending flange, d, which is hung on the pipes F, so as to support said section. It will be seen that by this construction I produce a gas-passage extending upwardly through and beyond the burner-tip within the chimney, and thence laterally, and subsequently downwardly and inwardly to the burner-tip. I do not wish to limit myself to the manner in which the several parts are constructed and put together to form this gas-passage, as they may be varied considerably in details, and the passage yet made to extend in the same directions. For instance, I may arrange inside the upper section, J, of the chimney a tube, of metal, conforming to said section in shape, but made sufficiently smaller to leave an annular space between it and said section, and I may close this space at the top and bottom and make the pipes F communicate with the upper portion and other pipes communicate with the lower portion and the outer portion of the coupling-piece E'. In either construction the gas will be thoroughly heated before arriving at the burner-tip.

K designates a deflector, which will preferably be made of glass, and has its upper edge extended along the burner-tip and bent inward toward the latter. This deflector rests upon the gallery H, and is of such size that a space is left between it and the burner-tip and another space is left between it and the lower section

of the chimney. The gallery is provided with openings *e* (see particularly Fig. 2) where the deflector rests upon it; hence provision is afforded for the entrance of air both outside and inside the deflector. Outside the pipe *P*, I preferably arrange some white material, *L*—such, for instance, as asbestos, or any material which will become incandescent when heated.

M designates a shade, which may be made of glass, metal, or any other suitable material, and of any appropriate shape. It is shown as having the upper edge turned inward and downward and resting upon a holder consisting of a ring, *N*, having its outer edge upturned. This holder is suspended by rods *O*, which hook over the upper edge of the section *J* of the chimney.

It is obvious that a circular row of burner-tips may be substituted for a single annular burner-tip.

I may extend the lower section of the glass chimney up over the upper section and grind it so that it will conceal the upper section.

What I claim as my invention, and desire to secure by Letters Patent, is—

1. The combination, with an annular burner-tip or series of burner-tips, of a gas-passage extending up within the same to a point considerably beyond the same and returning thereto, so as to be heated by the products of combustion passing through a chimney, substantially as specified.

2. The combination, with an annular burner-tip or a series of burner-tips, of a gas-passage, consisting of a pipe extending up from the center of a body-piece from which the burner tip or tips extend, and adapted to communicate with the nipple of a gas-fixture, a pipe or pipes extending laterally from the said pipe at a point considerably above the burner tip or tips, and pipes which are in communication with the said laterally-extending pipe or pipes and communicate with the burner tip or tips, substantially as specified.

45 3. The combination, with a burner tip or tips,

of a body-piece from which the same extend, a pipe, *E*, adapted to communicate with the nipple of a gas-fixture, a coupling-piece, *E'*, a pipe, *E''*, a number of pipes, *F*, a number of pipes, *G*, or a passage communicating with the coupling-piece, the pipe *P*, and the hub *b* of the body-piece, provided with a cavity communicating with the burner tip or tips, substantially as specified.

4. The combination, with a burner tip or tips, 55 of a body-piece from which the same extend, pipes forming a passage up within or between the burner tip or tips, thence back again, so as to communicate with the burner tip or tips, and comprising a pipe, *P*, and a white material, *L*—such as asbestos or any material which will become incandescent when heated—applied to the exterior of the pipe *P*, substantially as specified.

5. The combination, with an annular burner- 65 tip or a series of burner-tips, of a body-piece from which the same extends, a passage consisting of pipes extending up from the body-piece and back again to it, so as to then supply gas to the burner tip or tips, and a chimney composed of a lower section and an upper section, which is hung upon the said pipes, substantially as specified.

6. The combination, with a burner tip or tips, 75 of a body-piece from which the same extend, a passage consisting of pipes extending up from the body-piece and back again to it, so as then to supply gas to the burner tip or tips, a chimney-gallery extending from the body-piece, a chimney consisting of an upper section supported by the said pipes and a lower section supported by the chimney-gallery, a deflector supported on the chimney-gallery, and openings in the chimney-gallery admitting air within and outside of the deflector, substantially 85 as specified.

ANDREW B. LIPSEY.
